(57) **CLAIM**

I claim the ornamental design for an overhead cabinet, as shown and described.

DESCRIPTION

FIG. 1 is a perspective view of an overhead cabinet showing my new design;

FIG. 2 is a front elevation view thereof;

FIG. 3 is a top elevation view thereof;

FIG. 4 is a bottom elevation view thereof;

FIG. 5 is a left side elevation view thereof; and,

FIG. 6 is a right side elevation view thereof.

The cabinet is shown broken away to indicate indeterminate length, it being understood that the design continues uniformly along its length.

The broken line shown in FIG. 1 is for illustrative purposes only and forms no part of the claimed design.
